CLAIM

The ornamental design for a TT hatched socket for garden tool head, as shown and described.

DESCRIPTION

FIG. 1 is an isometric view of the TT hatched socket for garden tool head;

FIG. 2 is a front view of the TT hatched socket for garden tool head;

FIG. 3 is a back view of the TT hatched socket for garden tool head;

FIG. 4 is a left view of the TT hatched socket for garden tool head;

FIG. 5 is a right view of the TT hatched socket for garden tool; and,

FIG. 6 is a top view of the TT hatched socket for garden tool head.

The broken lines in the drawings illustrate portions of the TT hatched socket for garden tool head and form no part of the claimed design.

1 Claim, 6 Drawing Sheets
